UNITED STATES PATENT OFFICE.

FRANK L. O. WADSWORTH, OF SEWICKLEY, PENNSYLVANIA.

MEANS FOR DENSIFYING METALLIC SURFACES.

1,074,824:

Specification of Letters Patent.

Patented Oct. 7, 1913.

Application filed February 6, 1911. Serial No. 606,898.

To all whom it may concern:

Be it known that I, FRANK L. O. WADSWORTH, residing at Sewickley, in the county of Allegheny and State of Pennsylvania, a citizen of the United States, have invented or discovered certain new and useful Improvements in Means for Densifying Metallic Surfaces, of which improvements the following is a specification.

10 The invention relates to the densification of the surface portions of metallic articles, and has for its object the provision of improved means for effecting such densification, and in a more thorough and efficient 15 manner.

The surfaces of metallic articles have heretofore been densified by first rolling upon said surfaces closely arranged projections and depressions, and then rolling down 20 the roughened surfaces between smooth rolls. The rolls for roughening the surfaces of the metal piece have usually been marked by cutting their operating surfaces in annular 25 grooves and cross-grooves, thus forming upon them a multiple of projections of a quadrilateral cross-section. By marking the rolls as hereinafter described the expense 30 of marking is reduced, the pattern is more durable, and a more effective and thorough densification of the product is attained.

In the accompanying drawings Figure 1 is a plan view of a portion of a roll or other die surface embodying the invention; Fig. 2 is a cross-section on the line II—II of Fig. 35 1; Fig. 3 is a cross-section on the line III—III of Fig. 1; Fig. 4 is a view in elevation of a stand of rolls suitable for the practice of the invention, the reduced scale however not permitting a complete portrayal of 40 the marking; Fig. 5 is a perspective view of a portion of one surface of a metal plate after having been subjected to the action of one of the marked roll-surfaces; Fig. 6 is a view similar to Fig. 1 illustrating a modified 45 form of marking; Fig. 7 is a cross-section on the line VII—VII of Fig. 6; Fig. 8 is a view similar to Fig. 5 of the surface of the product of the roll or die of Fig. 6; Fig. 9 illustrates conventionally the roughening 50 and rolling down of the surface of a piece of metal.

In the embodiment of the invention illustrated in Fig. 1, the roll or other die surface for roughening the surface of the metal piece 55 is covered with pyramidal indentations 1 of

triangular cross-section. These indentations are of uniform dimensions and are arranged in rows, edge to edge, with the apices of the triangular edges of adjacent indentations in each row pointing in opposite directions, and each arranged apex to apex and base to base with like indentations in the adjacent rows. Thus, as shown, the edges of the indentations together form transverse and diagonal intersecting ridges or facets 2, 60 65 symmetrically disposed over the entire marked surface of the roll or die.

The operating surfaces of the rolls 3, 4 and 5 of the stand shown in Fig. 4, which form the four initial passes *a*, *b*, *c* and *d*, 70 may all be marked in the manner described, with indentations gradually decreasing in dimensions at each succeeding pass. The surface of the lower roll 3 in the fifth pass *e* may also be marked as shown, while the 75 surfaces of the rolls 4 and 5 forming the sixth pass *f* will be left smooth. It will be understood however that either or both surfaces of the piece may be roughened in as many or as few passes as may be desired, 80 and may be smoothed in another pass in the same stand of rolls or in a separate stand.

In the use of a stand of rolls such as is shown in Fig. 4, for the formation and treatment of a flat plate or strip of metal, 85 the piece after having been heated is first fed forward through the lower pass *a*, whence it emerges with both of its flat surfaces covered by upstanding adjacent pyramidal projections 6, as shown in Fig. 5, with 90 their bases abutting against each other, and all faces of each projection exposed to the effect of the air or other substance with which these marked surfaces may be brought into contact. The piece is then returned 95 through the upper pass *b* and the operation repeated, as also in the next passes *c* and *d*. In the fifth pass *e* the projections upon the upper face of the piece will be smoothed down, and in the final pass *f* the projections 100 on the lower face will be smoothed. In this final compression of the pyramidal marked surfaces each to a smooth surface, there will be a material densification of the surface portions of the piece in lines parallel 105 with the general plane of its surface.

In Fig. 6 there is illustrated another arrangement of the indentations in the die surface, the edges of corresponding indentations in adjacent rows facing in the same 110

direction, so that the apex of the edge of each indentation strikes the center of the base of the edge of an indentation in the next row.

5 By marking the operating surface of the roll or die with pyramidal indentations, with the edges of adjacent indentations coinciding as described, a much stronger and more durable die surface is obtained than in

10 the case of a surface provided with separate and distinct projections, while at the same time the maximum working and densifying action is insured. While the indentations may have more than three faces, it is pre-

15 ferred to make them of triangular cross-section as described, since there is thereby obtained a maximum of operative surface area for a given mass of metal. Thus not only is the metal piece most effectively

20 worked, but it is given a very large surface area exposed to the cooling effect of the rolls and of the surrounding atmosphere.

I claim as my invention:

1. A die for use in the process of densifying the surfaces of metallic articles by first roughening and then smoothing the surface to be densified, having formed in its operat-

ing surface closely adjacent pyramidal indentations.

2. A die for use in the process of densifying the surfaces of metallic articles by first roughening and then smoothing the surface to be densified, having formed in its operating surface pyramidal indentations, each edge of each indentation coinciding with an edge of an adjacent indentation.

3. A die for use in the process of densifying the surfaces of metallic articles by first roughening and then smoothing the surface to be densified, having formed in its operating surface pyramidal indentations of triangular cross-section arranged edge to edge.

4. A rolling mill for densifying the surfaces of metallic articles, having formed in the surface of one pass pyramidal indentations of triangular cross-section arranged edge to edge, and having a smooth-surfaced succeeding pass.

In testimony whereof I have hereunto set my hand.

FRANK L. O. WADSWORTH.
